SAFETY CONTROL DEVICE FOR A RIFLE WITH
A SCOPE

McEathron W. Wood, Charleston, W. Va.

Application May 26, 1953, Serial No. 357,431

1 Claim. (Cl. 42—70)

By way of explanation, it might be stated that in certain well known military rifle construction, the operation of the usual safety mechanism is difficult, especially when the rifle is equipped with the conventional scope sight.

It is therefore the primary object of the present invention to provide an attachment to be secured to the rear bolt face of the usual safety mechanism of a rifle, which will extend laterally from the safety mechanism to permit of ready access thereto, without interference due to the mounting of the scope sight thereon.

Another object of the invention is to provide a device of this character which may be readily and easily mounted on the safety mechanism, eliminating the necessity of making extensive alterations in the usual structure to mount the device.

With the foregoing and other objects in view which will appear as the description proceeds, the invention consists of certain novel details of construction and combinations of parts hereinafter more fully described and pointed out in the claims, it being understood that changes may be made in the construction and arrangement of parts without departing from the spirit of the invention as claimed.

Referring to the drawing:

Figure 1 is a fragmental elevational view of a military rifle equipped with a scope sight, and to which the attachment forming the subject matter of the present invention is secured.

Fig. 2 is a sectional view taken on line 2—2 of Fig. 1.

Fig. 3 is a rear elevational view of the attachment as secured to the rear bolt face of the safety mechanism.

Fig. 4 is a sectional view taken on line 4—4 of Fig. 3.

Referring to the drawing in detail, the stock of the rifle is indicated generally by the reference character 5, the barrel of the rifle being indicated by the reference character 6, while the scope sight which has been attached to the rifle in converting the rifle for ordinary use, is indicated by the reference character 7.

The reference character 8 indicates the safety bolt of the rifle, which is disposed directly under the scope sight, as clearly shown by Fig. 2 of the drawing.

In operating the safety mechanism, the bolt 8 is rotated, and in view of the location of the safety mechanism with respect to the scope sight, it is difficult for a person to manipulate the safety mechanism.

The enlarged end of the safety bolt 8 is bored at a point centrally thereof to receive the securing screw 9 which passes through an opening in one end of the arm

2

10 which is constructed of flat metal material having its side edges inclined, providing a substantially narrow end 11 through which the securing screw 9 extends, and a wide end 12, the end 12 being wide to provide sufficient space for the thumb and forefinger of the person using the gun, to readily grip the arm to move the arm and safety mechanism.

The wide end of the arm is formed with a depression 13 to accommodate the thumb so that the person using 10 the gun may securely grip the arm 10 in moving the arm.

The arm 10 is formed with a cut away portion 14 that fits against one edge of the scope sight 7 so that the movement of the arm will not in any way interfere with the proper setting of the scope sight.

As better shown by Fig. 4 of the drawing, a pin 15 is extended through an opening in said arm spaced from the securing screw 9, the pin 15 also passing into an opening formed in the rear surface of the bolt 8 preventing turning of the arm 10 with respect to said sliding bolt.

From the foregoing it will be seen that due to the construction shown and described, the person using the rifle which has been supplied with an actuating arm such as forming the subject matter of the present invention, 25 may by merely placing his thumb in the depression 13 move the arm 10 from the position shown in full lines in Fig. 3 of the drawing, to the position shown in dotted lines, thereby actuating the safety mechanism to release the safety mechanism.

30 The attachment not only provides means for operating the safety mechanism, but affords means whereby the safety mechanism may be quickly released which is absolutely necessary in the use of firearms such as rifles used in hunting large game.

35 Having thus described the invention, what is claimed is:

In a rifle having a barrel with a safety bolt, and a scope above the bolt; an attachment for the bolt to facilitate the movement of the bolt to released or locking position, said attachment comprising a tapered arm having a small 40 inner end and a large outer end, a screw extending through said small end and threaded into the rear end of said bolt, the large end of said arm projecting right-angularly from said bolt, said large end having a finger recess in the rear side thereof and said large end having 45 a recess in the upper edge thereof, whereby said arm may be raised to effect operation of said bolt in one direction, and a pin fixedly carried by said bolt laterally of and parallel with the axis thereof and projecting into said arm to hold said arm against movement relative to 50 said bolt.
